UNITED STATES PATENT OFFICE.

EDWIN G. BUSSE, OF CHICAGO, ILLINOIS, ASSIGNOR TO CHICAGO RAILWAY EQUIPMENT COMPANY, OF CHICAGO, ILLINOIS, A CORPORATION OF ILLINOIS.

REVERSIBLE STRUT FOR BRAKE BEAMS.

Application filed February 16, 1922. Serial No. 536,850.

To all whom it may concern:

Be it known that I, EDWIN G. BUSSE, a citizen of the United States, residing at Chicago, county of Cook and State of Illinois, have invented a certain new and useful Improvement in Reversible Struts for Brake Beams, of which the following is a full, clear, and exact description, such as will enable others skilled in the art to which it applies to make and use the same, reference being had to the accompanying drawings, forming part of this application.

Figure 1 is a sectional view through a brake beam showing my improved reversible strut in position.

Figure 2 is a similar view through the tension seat end of the strut, showing a modified form.

Figure 3 is a similar view of another modification.

Figure 4 is a view of another modified form.

This invention relates to a new and useful improvement in reversible struts for brake beams and is designed particularly as an improvement upon that form of reversible strut shown in the Johns Patent No. 470,682, dated March 15, 1892, and the Huntoon Patent No. 1,340,168, dated May 18, 1920; the objects of my present invention being to simplify the construction and by the use of bolts, rivets or other fastening devices, enable the beam to be repaired.

In the drawings, 1 indicates the compression member, and 2 the tension member of a trussed brake beam. 3 is the strut having openings 4 through which passes the pin on which the brake lever, not shown, is mounted. Each end of the strut shown in Figure 1 is provided with a hollow cylindrical trunnion-like extension 5 from the outer faces of which extend hollow bosses 6 forming pivotal members in axial alignment with the trunnions. These pivotal members are integral with the trunnions in Figures 1 and 2, but are shown as separate members in Figures 3 and 4. 7 indicates the casting or strap which embraces the compression member 1 and is provided with an inwardly extending flange 8 through and beyond which the boss 6 extends. The inner end of this casting is provided with outwardly extending flanges 9 which rest upon the end wall of the strut. These flanges have recesses 10 which cooperate with lugs 11

whereby the strut may be held in adjustable position for right and left hand brake levers.

12 indicates a casting whose outer end is provided with a seat for the tension member 2, said casting having an inwardly extending flange 13 through and beyond which projects a boss 6^a on the outer end of the strut. The inner end of casting 12 is provided with an outwardly extending flange 14 which rests against the end wall of the strut. 15 indicates a rivet or other fastening device, such as a bolt, by which the strut is secured in proper adjusted position to the casting 7. It will be noted that the outer head of this rivet (or bolt head) bears against the face of the boss 6 and is not in direct contact with the flange 8. Hence by the clearance thus provided, the parts may be said to be held together by the pressures exerted by the compression and tension members but should either of these members break, the rivet or other fastening device would prevent separation of the parts. The rivet or fastening device 16 which secures the tension member seat to the inner end of the strut likewise bears against the outer face of the boss 6^a.

I do not wish to confine myself to the use of the recesses 10 and lugs 11, as a means for holding the strut in adjusted position, as other well-known means may be employed for this purpose. The tension seat is preferably left free to rotate on the inner end of the strut and has no means for holding it in any fixed position.

In Figure 2 I have shown an inversion of the parts illustrated in Figure 1 in which the strut 17 has a flange 18 and a cylindrical bore or seat in its outer end beyond this flange. 19 is a tension seat having an inwardly extending boss 20 which projects slightly beyond the inner face of flange 18 so that when the rivet 21 is placed in position it will be seated against the inner face 100 of boss 20, and extending over the inner marginal edges of flange 18 will prevent accidental displacement of the parts while permitting their rotation.

In Figures 3 and 4, I have shown modified forms in which strut 17 has a socket in its end, said socket being formed by an apertured seat 18, as shown in Figure 2. Instead of having a pivotal member or boss formed integral with the parts, I provide the tension

rod seat 19 with a registering aperture in its inner wall and arrange a separate pivotal member or sleeve 22 in the registering apertures, which sleeve is slightly longer than 5 the thickness of the two contiguous apertured walls. A rivet 23 is shown as a fastening device, and when upset this rivet will have both of its heads bearing directly upon the end faces of the sleeve in the manner 10 heretofore described with relation to the boss shown in Figures 1 and 2.

In Figure 4, I have shown the sleeve as having an outwardly extending flange 24, which flange is designed to receive the upset 15 end of the rivet 23 and prevent the marginal edges of the upset head of the rivet from contacting with the tension rod seat, which might occur in the form shown in Figure 3.

In all the forms shown, it will be observed 20 that the rivet heads engage opposite faces of the pivotal member whether boss or sleeve, and, consequently, the parts mounted upon the pivotal member are free to rotate without binding contact with the rivet in each 25 instance. These bosses or sleeves are, therefore, designated as pivotal members, and when the rivets or other devices are in

place, said pivotal members and their carried fastening devices serve as binding or holding members.

What I claim is:

1. In a brake beam, the combination of compression and tension members, seats therefor, a strut, a trunnion-like extension on one of said parts, a seat in a companion part for receiving said trunnion-like extension, a pivotal member arranged in axial alignment with respect to said parts, and holding devices which engage the opposite faces of said pivotal member.

2. In a brake beam, the combination of tension and compression members, seats therefor, a strut, interengaging trunnion-like extensions and recesses in said parts, respectively, pivotal sleeves on which said parts have a relative turning movement, and fastening devices having shoulders which bear against the end faces of said pivotal sleeves for holding said sleeves in position.

In testimony whereof I hereunto affix my signature this eleventh day of February, 1922.

EDWIN G. BUSSE.
